Primary Examiner — David G Muller(74) *Attorney, Agent, or Firm* — Michael Best & Friedrich LLP(57) **CLAIM**

The ornamental design for an insemination syringe, as shown and described.

DESCRIPTION

FIG. 1 is an isometric view of the insemination syringe;
FIG. 2 is a left side view thereof;
FIG. 3 is a right side view thereof;
FIG. 4 is a front view thereof;
FIG. 5 is back view thereof;
FIG. 6 is a top view thereof; and,
FIG. 7 is a bottom perspective view thereof.
